Samuel B. Rickards

UNITED STATES PATENT OFFICE.

SAMUEL B. RICKORDS, OF SEYMORE, IOWA, ASSIGNOR OF ONE-HALF TO
JOHN SHANNON, OF SAME PLACE.

DESIGN FOR A COPING FOR GRAVES.

SPECIFICATION forming part of Design No. 29,860, dated December 20, 1898.

Application filed September 6, 1898. Serial No. 690,335. Term of patent 3½ years.

To all whom it may concern:

Be it known that I, SAMUEL B. RICKORDS, a citizen of the United States, and a resident of Seymour, in the county of Wayne and State of Iowa, have invented and produced a new and original Design for a Coping for Graves, of which the following is a specification, reference being had to the accompanying drawings, forming a part thereof and illustrating the same, and in which—

Figure 1 is a top view and diagrammatical outline of the ornamental configuration. Fig. 2 is a sectional view taken on the line 2 2 of Fig. 1 and looking toward one end of the coping. Fig. 3 is a sectional view taken on the line 3 3 and looking toward one side of the complete form.

As shown in Fig. 1, the leading or material feature of my design is the peculiar shape, as

outlined in Fig. 1, in which A and B are the 20 parallel mating parts, joined together at their ends to produce an oblong open space in the interior having semicircular-shaped ends. The four exterior corners C project outward relative to the center at angles of about forty-five (45) degrees and are angular in shape on their vertical lines and curved outward and downward on their top surfaces. 25

Having thus described my invention, what I claim as new, and desire to secure by Letters 30 Patent therefor, is—

The design for a coping for graves, as herein shown and described.

SAMUEL B. RICKORDS.
